DICTATING MACHINE

James J. Clerkin, Jr., and Leslie T. Carr, Winnetka, Ill.,
assignors to Comptometer Corporation, Chicago, Ill.,
a corporation of Illinois

Filed July 17, 1959, Ser. No. 56,822

Term of patent 14 years

(Cl. D26—14)

Fig. 1.

Fig. 2.

Fig. 4.

Fig. 3.

Fig. 5.

Fig. 1 is a perspective view of a dictating machine, showing our new design;

Fig. 2 is a front elevational view;

Fig. 3 is an end elevational view at a reduced scale from Figures 1 and 2, the opposite end being substantially a mirror image thereof;

Fig. 4 is a rear elevational view at the same scale as Figure 3; and

Fig. 5 is a bottom plan view thereof at the scale of Figures 3 and 4.

The dominant features of our new design are shown in full, unbroken lines in the drawings.

We claim:

The ornamental design for a dictating machine, substantially as shown and described.
